ANDREW E. WHITMORE, OF BOSTON, MASSACHUSETTS.

Letters Patent No. 93,026, dated July 27, 1869.

IMPROVEMENT IN SLIDING CALIPERS.

The Schedule referred to in these Letters Patent and making part of the same.

To all to whom these presents shall come:

Be it known that I, ANDREW E. WHITMORE, of Boston, in the county of Suffolk, and Commonwealth of Massachusetts, have made an invention of an original and useful instrument for determining the thickness of sheet-metals, diameters of cylinders, &c., which may be termed Self-Regulating Calipers; and do hereby declare the following to be a full, clear, and exact description thereof, due reference being had to the accompanying drawings, making part of this specification, and in which—

Figure 1 is a plan,
Figure 2 is a side elevation,
Figure 3, an end elevation,
Figure 4, a vertical and longitudinal section, and
Figure 5, a transverse section of an instrument embodying my invention.

The invention herein to be described relates to a stationary and a movable jaw, mounted upon a tubular shank or bar, enclosing a male screw, which passes through and so actuates the movable jaw as to produce sliding movements of it upon the shank, toward and away from the stationary jaw, which is fixed to the shank, the said shank, at its opposite end, being provided with a fixed disk or collar, upon which is engraved a scale for determining the infinitesimal fraction of an inch which is measured by the instrument, an adjustable index-pointer being applied to the adjacent extremity of the screw, and in conjunction with the scale before mentioned, in such manner as to be readily loosened upon the screw and returned to the normal or zero-point of the scale, should any disarrangement or discrepancy manifest itself after moving the adjusting-nut of the movable jaw upon the screw which actuates it, the whole being as hereinafter explained.

In the drawings, to which allusion has before been made as accompanying this specification, and which illustrate my invention—

a denotes an attenuated tubular bar, having affixed upon one extremity, and at right angles to its general axis, a stationary jaw, *b*.

Within the bore of the bar *a*, (which may be square or polygonal,) and turning in suitable bearings formed in each end thereof, I dispose a long male screw, *c*, the extremity of this screw farthest from the fixed jaw of the instrument, having applied to it a thimble, *d*, such thimble in turn being provided with an index-pointer, *e*, projecting from its front face, at right angles to its bore, and impinging against the rear face of a dial-plate, *f*, affixed to or making part of the contiguous end of the bar *a*, the said outer face of the dial-plate having engraved upon it a scale to denote the fractions of an inch, the divisions of such scale vary-

ing in number with the degree of exactitude which it is intended the instrument shall register.

A scale of inches is to be engraved upon one or both sides of the bar *a*.

The movable jaw of the instrument is shown at *g*, as of like size and shape with its fellow-jaw, and sliding easily upon the bar *a*, a sectional nut, *h*, being swivelled within its upper part in such manner as to be depressed into engagement with the screw *c*, or elevated from contact therewith.

Each extremity of the screw *c* should be provided with a milled head, *i*, for rotating it.

The above comprises the constituent parts and mechanical construction of an instrument embodying my invention, its action being as follows:

For measuring large bodies, when great accuracy is not essential, the movable jaw may be used in connection only with the scale upon the side of the bar *a*.

The adoption of the adjustable sectional nut is to allow of rapid changes of the movable jaw, toward or away from the stationary jaw, in order to adapt the instrument to great variations in distances measured by it.

The employment of the sectional nut, as described, effects an economy in the wear upon the screw, and in the time required to use the instrument.

The exactness of measurement of which the instrument is capable, is, of course, directly dependent upon the number of threads of the screw to an inch, and of the number of the divisions of the scale upon the dial-plate at the end of the bar *a*.

In the present instance, the screw is cut with twenty-five threads to the inch, and the circular scale is divided into forty points; hence, a partial turn of the screw, sufficient to move the indicator-point *e* the distance of one division upon the scale, will produce a sympathetic movement of the movable jaw upon the bar *a* to the extent of one-thousandth part of an inch, this number being the multiple of the number of threads to the inch of the screw, and of the subdivisions of the scale.

It will probably never be found, in practice, necessary to exceed the above fractions of an inch.

The object in applying the sleeve *d* to the screw *c*, in an adjustable manner, is to enable the index-pointer to be set at the zero of its scale, when the movable jaw coincides exactly with the scale upon the side of the bar *a*, or when the two jaws are in contact with each other.

The adoption of the sectional nut, as before observed, allows of rapid and extended movements of the movable jaw, which would otherwise require much time to effect, were the screw alone employed for this purpose.

By encasing the screw within the bar of the instrument, it is protected from injury, which would inevitably result to it but for this or some analogous protection.

I would remark that I have contemplated applying the intermediate jaw to the bar in such manner as to be able to secure it thereto in an adjustable manner, independent of the screw, and to adapt the screw to produce movements of the outer jaw for giving the small fractional parts of the measurements.

By this mode, the threads of the screw need only be cut upon a small portion of the length of the rod of which it is composed, and the index-pointer may be more readily adjusted.

Having thus described the nature, construction, and uses of my invention,

What I claim to be novel and original with myself, as well as useful to the public, and desire to secure by Letters Patent of the United States, is as follows:

Claim.

I claim the combination and arrangement of the swivelling or socket-screw, and sectional saddle-nut *h*, with the movable jaw of a beam-caliper, substantially as and for the purposes shown and set forth.

A. E. WHITMORE.
